UNITED STATES PATENT OFFICE.

SAMUEL P. BELT, OF CHERRYDALE, VIRGINIA, AND JOSEPH W. BELT, OF OKLAHOMA,
OKLAHOMA.

LIQUID-OPERATED DAMPER-REGULATOR.

1,071,864.

Specification of Letters Patent.

Patented Sept. 2, 1913.

Application filed December 2, 1911, Serial No. 663,583. Renewed January 29, 1913. Serial No. 745,006.

To all whom it may concern:

Be it known that we, SAMUEL P. BELT and JOSEPH W. BELT, citizens of the United States, residing at Cherrydale, Virginia, and at Oklahoma, Oklahoma, respectively, have invented certain new and useful Improvements in Liquid-Operated Damper-Regulators, of which the following is a specification.

10 This invention relates to damper regulators, and especially to means for operating draft dampers of steam boilers.

The object of the invention is to provide means for operating dampers by water pressure from a boiler so that a damper may be operated at the least variable steam pressure of the boiler.

A further object of the invention is to provide in a device for operating dampers by water or other fluid pressure, such novel and peculiar construction and arrangement of parts as will insure the operation of the damper during the least variable steam pressure of the boiler, and which will equalize the water pressure on certain parts of the device, and thereby avoid friction between said parts in a damper-working operation.

A still further object of the invention is to provide, in a damper operating device, a special cylinder having water connections with a steam boiler and with a damper cylinder, and a special piston for circulating the water to and from the damper cylinder through the piston cylinder.

35 Various other objects, advantages, and improved results are attainable in the practical application and working of the invention.

In the accompanying drawings forming 40 part of this application: Figure 1 is a side elevation, showing the application of the invention. Fig. 2 is a central vertical section. Fig. 3 is a perspective view of the piston. Fig. 4 is a perspective view of the piston-cylinder.

The same reference characters denote the same parts throughout the several views of the drawings.

In carrying out our invention we employ 50 a damper cylinder 1, having a piston 2, and a piston rod or stem 3, connected with an ordinary damper 4, by a lever 1^a, and a link 2^a. The lower end of the cylinder 1 is provided with a pipe nipple or coupling 5, and 55 said cylinder is supported by a base 6 at-

tached to and projecting from a steam chest 7, the parts of which are secured together by suitable bolts 8, so as to secure a diaphragm 9 within the steam chest, which is supplied with steam by means of a pipe 10, 60 from a steam boiler 5^a, so that the steam pressure of the boiler is made against the under side of the diaphragm. A cylinder 11 projects from the upper portion of the steam chest, and such cylinder has a water 65 induction port 12, and a water exhaust port 13. Pipes 14 and 15 lead to and from the ports 12 and 18 respectively, for supplying water or other motive fluid to the cylinder 11, and said pipes may be connected with 70 the water-leg of the boiler, or with such other source of liquid supply as desired. A water channel or duct 16 is formed on the cylinder 11, and said duct connects a water port 17 with a water port 18. The 75 ports 17 and 18 are formed in the cylinder 11, out of the diametrical lines of the ports 12 and 13, respectively, and the upper portion of the duct 16 has a nipple 19, for a pipe 20, which is attached to the nipple 5, 80 so that the pipe 20 is in constant communication with the duct 16, opposite the port 17, and the duct is in constant communication with the port 18.

Having provided a special cylinder, as 85 above described, we provide said cylinder 11 with a special piston 21, having a stem 22 working in and adjustable at the top of the cylinder 11 by means of a set screw 3^a, and a follower 4^a. The piston is cushioned 90 at the top by means of a spiral spring 22^a seated on a shoulder 23 of the piston, and working against the follower, and the piston has a disk-head 24 working in the upper portion of the steam chest 7, and engaged 95 by the diaphragm 9 for operating the piston. In order to establish communication between the ports 12 and 17, and communication between the ports 13 and 18, the piston is provided with an upper annular 100 groove 25, and a lower annular groove 26. The groove 25 forms an induction water channel through the cylinder 11, and the groove 26 forms a water exhaust or return channel through the cylinder to the boiler. 105 The grooves are at least twice the width of the ports 12, 13, 17 and 18, so that during the operation of the piston the ports 13 and 17 are opened and closed with respect to the grooves 25 and 26 without closing the ports 110

12 and 18, whereby the piston is perfectly balanced laterally under the pressure of water to and from the cylinder 11. Owing to the relative arrangement of the ports with respect to the piston channels, and when the stroke of the piston is properly adjusted, the channel 25 is never out of communication with the port 12, and the channel 26 is never out of communication with the port 18, so that an upward movement of the piston, under pressure of steam on the diaphragm, will close the damper, and a reverse movement of the piston, by reason of low steam pressure, will open the damper. It should be understood that various mechanical changes and variations may be made in the practical construction and application of the invention, and that the size, shape, and material may be modified, without departing from the spirit of the invention as expressed in the claims to follow.

Having thus described our invention what we claim as new and desire to secure by Letters Patent is:—

25 The combination with a fluid-operated damper for steam boilers, a piston connected

with the damper, and a cylinder for the damper-piston, of a cylinder having a steam chest connected with the boiler, a pair of fluid-ports on opposite sides of this cylinder above the steam chest, the ports on one side being out of the horizontal plane of the ports on the other side and adapted to supply motive fluid, a fluid duct in the wall of the ported cylinder for connecting the ports on the other side, a pipe connecting said duct with the damper-cylinder, a piston having annular fluid channels cooperating with the said ports so as to be balanced by fluid pressure through the ported cylinder, a piston-head working in the steam chest and closing communication between the chest and the ported cylinder, and means for cushioning the channeled piston.

In witness whereof we hereunto set our hands in the presence of two witnesses.

SAMUEL P. BELT.
JOSEPH W. BELT.
